UNITED STATES PATENT OFFICE.

ERNEST MOSS, OF CHRISTCHURCH, NEW ZEALAND.

IMPLEMENT RAISING AND DEPTH-REGULATING MECHANISM.

1,406,273.

Specification of Letters Patent. Patented Feb. 14, 1922.

Application filed November 18, 1919. Serial No. 338,875.

To all whom it may concern:

Be it known that I, ERNEST Moss, a subject of the King of Great Britain, residing at Dallington, Christchurch, New Zealand, 5 have invented new and useful Improvements in Implement Raising and Depth-Regulating Mechanism, of which the following is a specification.

This invention relates to the raising and 10 lowering of plows and other implements as required when turning the headlands and for regulating the depth of the work.

It is the object of the present invention to provide a simple and novel construction applicable alike to implements of the walking, 15 riding or tractor-drawn types, whereby the said operations may be performed by the plowman or driver by a simple manipulation which calls for no physical effort.

20 The invention is such that it may be applied in the form of an attachment adapted to be mounted upon the frame of the implement or upon the hand-lever or other known or existing means of depth adjustment which 25 latter arrangement is considered preferable inasmuch as it affords a ready means for obtaining the general setting of the implement as required for various classes of work.

In order that the nature of the invention 30 and its construction may be clearly understood, reference will now be made to the accompanying sheet of drawings in which;

Figure 1. is a perspective view of a double furrow walking plow showing the invention 35 applied thereto.

Figure 2. shows the invention as viewed from the outer side, or side away from the plow, the position of the parts when the plow is in its lowest condition being shown 40 in full lines, while the position of such parts when the plow is in its highest condition is indicated in dotted lines.

Figure 3. shows the device as viewed from the inner side, illustrating the means employed for controlling and operating the 45 deterrent or locking means.

Figure 4. shows the device as in Figure 2, but with the quadrant and gear-wheels removed, in order to illustrate the means employed for locking the sun-wheel for rotation, and,

Figure 5. shows a construction whereby the stub-axle of any land-wheel may be attached to the planet-wheel of the device.

55 In carrying the invention into effect the construction comprises a suitable plate or

base 1 adapted to be rigidly secured to the plow-frame 2 or to the lower end of the hand-lever 3 or, if so desired, such base may be included integral with either of such 60 parts.

As here shown, the base 1 is attached to the hand-lever 3 by means of a bolt or stud 4 passing through the hole or eye in the lower extremity of the latter and secured 65 therein by means of a nut 6. To hold it rigidly in place and to prevent it from turning or becoming loose, the said base is formed with an arm or portion 7 which extends upward with the hand-lever for a 70 suitable distance and terminates at its upper end in a T-shaped formation 8 having a pair of returned lugs 9 through which are tapped a pair of set-screws 10 adapted to bear against the upper and lower edges of 75 the hand-lever (as clearly shown in Figure 3).

Pivoted upon the base, as by means of the said bolt or stud 4, is a member 11 upon the portion of which projecting upon the 80 forward side of the said pivot 4, and at a suitable distance or radius from the latter, is carried the land-wheel 12, the arrangement being such that by turning the said member 11 in one direction or the other the 85 implement will be raised or lowered in relation to the hand-wheel.

Locking means are provided also for retaining the said member 11 in each of its various positions. For this purpose the 90 member 11 preferably, though not necessarily, takes the form of a quadrant, as here shown, having at a suitable radius from its said pivot 4 a series of notches, teeth or projections 13 adapted to be engaged by a 95 detent mounted upon the base 1 or other fixed point in relation to the frame of the implement, or the hand-lever as the case may be.

When the implement is in the raised condition therefore, the withdrawal of the detent from the teeth 13 of the quadrant will permit such implement to sink by gravity.

For the purpose of raising the implement, a sun-wheel 14 is revolvably mounted upon the base 1 or its equivalent and concentrically with the said pivot 4. The teeth of the said sun-wheel 14 intermesh with those of a planet-wheel 15 which is rotated by the hand-wheel 12. Under normal conditions both sun and planet-wheels revolve idly 110 upon their respective axes but when lifting of the plow is required the sun-wheel is

locked from rotation thus causing the planet-wheel, which continues to revolve with the land-wheel, to perform a planetary or epicyclic movement around such sun-wheel, which results in a turning of the member or quadrant 11 upon its pivot 4 and a consequent raising of the implement (as indicated in dotted lines Figure 2).

For the purpose of so locking the sun-wheel a plate or disc 16 (Figure 4) is attached to such sun-wheel or rigidly connected therewith as by means of a sleeve 17 as here shown, such disc or plate 16 being formed or provided with one or more suitable notches, teeth or projections 18 adapted to be engaged by a detent carried upon the base 1 or other fixed point in relation to the frame of the implement or the hand lever as the case may be.

If so desired however, the disc or plate 16 may be dispensed with, in which case suitable formations in lieu of the notches 18 will be provided upon the sun-wheel 14 itself.

In practice a single detent or sliding bolt 19 is provided and adapted, when in one extreme position (as indicated in full lines Figure 4) to engage the teeth 13 of the quadrant and in its other extreme position to engage in one of the notches 18 of the disc 16 and so lock the sun-wheel from rotation, while in its intermediate position such detent 19 will be clear of both disc and quadrant and will therefore, permit the implement to sink by gravity.

As here shown the detent 19 is slidably mounted between guides 20 upon the base 1, while for the purpose of so operating such detent a bell-crank lever 22 is pivoted as at 23 upon the base 1, the short arm of such lever being connected with, such detent 19 as by means of a screw or the like 24 passing through a slot 25 in the base 1, as clearly shown in Figure 3. To the other or longer arm of the said lever 22 is attached a cord 26 or the like 26 adapted to be manipulated by the plowman or driver from his ordinary position either walking in rear of the implement, or seated on the latter or on the tractor as the case may be.

In cases where it is desired to manipulate the device with a forward pull of the cord 26, the lever 22 may be reversed so as to place its pivot 23 to the rearward instead of the forward side of the detent 19 or the same purpose may be accomplished by the employment of a bell-crank, a sheave-block or other suitable means for reversing the direction of the cord 26.

For the purpose of normally carrying the detent into the position of engagement with the teeth 13 of the quadrant a spring or the equivalent 27 is employed and adapted to exert a tension upon the lever 22 in the required direction, or again the same purpose 65 may be effected by the employment of a

spring adapted to act directly upon the detent 19 itself.

The arrangement is such that if the cord is pulled for a slight distance the detent will be drawn out of engagement with the quadrant and placed in the intermediate or neutral position thus permitting the implement to sink by gravity, while by pulling the cord for a somewhat greater distance the detent will be caused to engage the disc of the sun-wheel and thus effect the raising of the implement in the manner already described. Upon the cord being released when the quadrant is in any position the spring will cause the detent to engage the nearest notch 13 in such quadrant.

If desired however, a brake, clutch, or other suitable means may be employed for locking the sun-wheel in the required manner.

The planet-wheel may be attached to the land-wheel in any suitable manner so as to be operated directly thereby or the two may be connected by means of suitable gearing. In cases where it is desired to apply the device to various standard makes of plows without alteration or discarding any of the parts of the latter, the construction shown in Figure 5 is employed. In this case formed integral with the planet-wheel 15 or mounted thereon, is a lug 28 to which the stub-axle 29 of the land-wheel 12 is bolted as by means of the nut 30, while to provide the necessary drive, one or more projections 31 are formed upon the lug 28 and adapted to engage the spokes 32 of such land-wheel in any suitable manner.

Suitable means are provided for automatically causing the detent 19 to release the disc 16 and engage the projections 13 of the quadrant at the completion of the lifting movement of the device.

As here shown these means comprise a projection 33 upon the detent 19 and adapted to extend from the face of the latter into a suitable clearance slot 34, such slot having a suitable inclined surface or formation 35 adapted, when the extremity of the lifting movement is reached, to so engage the projection 33 as to operate the detent 19 in the required manner.

It will be understood that by applying the device to the hand-lever of the implement, as here shown, the ordinary screw 36 or other standard means of adjustment may be employed for obtaining the general setting of the implement as required for various classes of work.

If so desired however, as already mentioned, the hand-lever may be dispensed with and the device applied directly to the frame of the implement.

It will be understood also that the device may be applied to any or all of the wheels of the plow or any other implement in

which lifting or depth regulation is required.

I claim:

1. In an agricultural implement, the combination of a frame, a hand-lever pivoted on said frame, a base adjustably secured to one end of said lever, a lifting member pivoted on said base in juxtaposition thereto and adapted to raise or lower the frame, 10 said lifting member being provided in one side thereof with a plurality of teeth, a member slidable on the side of said base adjacent to said pivoted member and having one end adapted to engage said teeth thereby to retain 15 said pivoted member in various positions of adjustment, a land wheel mounted for rotation on said pivoted member and spaced radially from the pivot of said member, a sun wheel mounted for rotation on 20 said pivot, a planet wheel carried by said land wheel in mesh with said sun wheel, a ratchet disk carried by said sun wheel in the same vertical plane as the teeth of said pivoted member, whereby the opposite end 25 of said slidable member will engage said disk and lock the sun wheel against rotation,

means for releasing said slidable member from said disk and from said teeth, and cooperating means carried by said slidable member and pivoted member for releasing 30 the slidable member from said disk independently of said last means.

2. In an agricultural implement, the combination of a frame, a lifting member in pivotal connection with said frame, a sun 35 wheel carried by said lifting member and mounted for rotation concentrically with the pivot of said member, a planet wheel carried by the lifting member in intermeshing relation with said sun wheel, a land wheel 40 having a stub axle, means carried by said planet wheel for rotatably supporting said stub axle in concentric relation with the planet wheel, and means carried by said last means for engaging said land wheel thereby 45 to rotate the same with said planet wheel.

In testimony whereof I have signed my name to this specification.

ERNEST MOSS.
